DESIGN FOR A NECKTIE

Maurice Urdang, New York, N. Y.

Application May 26, 1943, Serial No. 110,295

Term of patent 3½ years

To all whom it may concern:

Be it known that I, Maurice Urdang, a citizen of Lithuania, residing at New York, in the county of New York and State of New York, have invented a new, original, and ornamental Design for a Necktie, of which the following is a specification, reference being had to the accompanying drawing, forming part thereof.

In the drawing the figure is a plan view of a necktie showing my new design.

I claim:

The ornamental design for a necktie, as shown.

MAURICE URDANG.
